K. LAUER

INTERNAL GAUGE

Filed Nov. 29, 1921

UNITED STATES PATENT OFFICE.

KARL LAUER, OF ESSEN, GERMANY, ASSIGNOR TO FRIED. KRUPP AKTIENGESELLSCHAFT, OF ESSEN-ON-THE-RUHR, GERMANY.

INTERNAL GAUGE.

Application filed November 29, 1921. Serial No. 518,612.

To all whom it may concern:

Be it known that I, KARL LAUER, residing at Essen, Germany, a citizen of the German Republic, have invented a certain 5 new and useful Improvement in Internal Gauges, of which the following is a specification.

The present invention relates to internal gauges having an adjustable plunger body 10 and a member angularly displaceable thereto provided with a conical surface actuating the plunger. In known gauges of this kind the body rests upon the conical surface, which body is carried in a tight fitting cylindrical boring. Such a construction has the disadvantage, that a wearing away may occur which makes possible a lateral displacement of said body with a consequent error in measurement, which cannot be corrected without renewal of the parts guiding said body. The object of the present invention is to make impossible such a wearing away through a special type of construction of the above named guiding parts; 25 and secondly to provide a device, which in the simplest manner makes it possible to counteract the unfavorable action of any wear of the guiding parts when constructed in accordance with the present invention.

30 In the accompanying drawing an embodiment of the present invention is illustrated showing an internal caliper gauge having an indicating lever device and of which:

35 Fig. 1 is an elevation of the gauge with a portion broken away;

Fig. 2 an axial longitudinal section thereof;

40 Fig. 3 a transverse section along line 3—3 of Fig. 2 seen from the left;

Fig. 4 a transverse section along line 4—4 of Fig. 2 also seen from the left and

45 Fig. 5 a section along line 5—5 of Fig. 2 seen from above.

The gage body consists of two tubular parts A and A¹ which are detachably screwed together.

The part A is provided with a longitudinal slit on its threaded end engaging the 50 part A¹ and with a tapered thread a² over which an internally threaded nut B is screwed. By means of the nut B the slit end of the part A is tightened down over the part A¹, which makes impossible any 55 unintentional displacement between the two

parts A and A¹. The gage body is provided with an inner thread a³ in its portion A into which a sleeve C having a corresponding exterior thread is screwed (see Fig. 2). Surrounding the sleeve C is arranged a 60 thimble D which is rigidly secured on the sleeve C by means of a set screw E and a lock nut F. The thimble D fits tightly around the cylindrical end of the gage body portion A. Upon the latter is provided a 65 millimeter graduation a⁴, while the thimble D carries circumferential graduations d¹. In the position shown on the drawing the thimble D is set at zero position. A sleeve G is further provided, which is freely rev- 70 oluble in the sleeve C, and extends at both ends outside this latter. On the end of the sleeve G, that reaches beyond the sleeve C to the right in Fig. 2, is threaded a housing H of an indicating device. This housing is 75 rigidly connected with the sleeve G by means of a set screw J and engages with the end face of the sleeve C without play.

The part of the sleeve G that reaches beyond the left-hand end of the sleeve C 80 in Fig. 2, carries a circular stepped extension g¹ against which the left-hand-end-face of the sleeve C contacts without play, see Fig. 2. The stepped extension g¹ also serves as a bearing for the sleeve G in the gauge 85 body. A longitudinal slit g² is provided in the extension g¹ with which a guiding key a⁵, secured in the gauge body, engages (see Figs. 2 and 4). The sleeve G may consequently be displaced axially but cannot 90 be turned in the gauge body.

A stepped rod K, partly enclosed by the sleeve G is slidably mounted in the gauge body A A¹. This rod K reaches into the housing H through a boring h¹ provided in 95 the bottom of said housing. A cylindrical stop-piece k¹ is rigidly connected with the end of the rod K that reaches into the housing H, the diameter of said stop-piece being greater than the diameter of the boring h¹. A stud M actuated by a spring, not shown, contacts with the stop-piece k¹ which stud is connected through a contacting member, likewise not shown, with the pointer N of an indicating device N n¹. The 105 stop-piece k¹ contacts with the bottom of the housing H under the action of a spring P which abuts at one end against a shoulder k² on the rod K and at the other end against an inner cylindrical abutment g³ of the 110

sleeve G. The cylindrical abutment g^3 forms the end of an enlarged boring g^4 of the sleeve G, the diameter of which boring is somewhat larger than the diameter of 5 the portion of the rod K forming the shoulder k^2 , so that a mutual displacement between the sleeve G and the rod K is possible.

The end of the rod K which lies to the left in Fig. 2 is conical. Three balls Q rest 10 on this conical surface k^3 and a plunger T, actuated by a spring R, contacts with each of said balls. These plungers T are displaceable perpendicularly to the direction of movement of the rod K. Their work measuring surfaces, that is their ends t^1 are situated 15 on a circle the diameter of which is the fundamental measure of the gauge, when the thimble D is in its zero position, see Fig. 3. The balls Q are guided in runways 20 a^6 on the side away from the rod K, which runways are formed by the flat surfaces a^7 placed at an angle to each other, see in particular Fig. 5. On account of the action of the spring P and the conical surface k^3 , the 25 balls Q are permanently kept in contact with the runway surfaces a^7 . With their halves directed towards the rod K the balls Q rest in half-cylindrical races a^8 .

The described caliper gauge is intended 30 for measuring bores or counter-bores, the diameter of which is greater than the above mentioned fundamental measure of the gauge, yet not over a certain maximum range.

35 When a bore is to be measured, the gauge is inserted in the bore with its end carrying the plungers T, and the thimble D turned. The sleeve C, which is rigidly connected with the thimble D is consequently screwed 40 into the gauge body A A^1 . The displacement of the sleeve C is communicated to the sleeve G (which latter is secured against turning by the key a^5), and to the housing H of the indicating device connected therewith and also to the rod K through the intermediary of the spring P, the stop k^1 remaining 45 still in contact with the bottom of the housing H by being actuated by the spring P. Through the axial displacement of the rod K, the balls Q as well as the plungers T are pushed outwards by virtue of the conical surface k^3 . The plungers T will finally come with their measuring surfaces t^1 , in contact with the walls of the bore to be calibrated. As soon as this takes place on further rotation of the thimble D, the sleeve C and the housing H will be displaced relative to the rod K, the spring P being compressed. As a consequence the stud M connected 55 with the pointer N will be displaced so that the latter will deflect. The turning of the thimble D is then continued until the pointer registers with the zero mark of the

scale n^1 . As soon as this takes place the tension of the spring P and therewith the 65 pressure exerted upon the plungers T will have attained such an amount that a perfect contact of the measuring surfaces t^1 with the inner wall of the bore is effected. The diameter of the bore is now determined 70 by reading off the setting of the thimble D and by taking regard to the fundamental of the gauge.

Practically no wear of the guiding means of the plungers T is possible, because axial 75 forces only are transmitted to the plungers T. Further any wear of the guiding means for the balls Q can only cause the formation of new grooves into which the balls Q should necessarily be pressed without side play by 80 the spring P, because they bear permanently, under the action of the spring P and the conical surfaces k^3 , against the faces a^7 , and this only at one point of each face a^7 . When such a wearing down does occur, the distance between the stud M, connected with the pointer N, and the contact points with the balls Q is increased, and as a consequence 85 a faulty measurement will be indicated on the scales a^4 , d^1 . This may however be corrected in the simplest manner. In this case the caliper gauge is inserted with its plungers T into a ring-gauge; the thimble D is thereupon set to the measure corresponding to the diameter of the ring-gauge, 90 the nut B then loosened and the part A^1 screwed further into the part A, until the pointer N indicates zero. The nut B is then tightened and the gauge is again ready for 95 use.

Claims—

1. A caliper device comprising a supporting casing, a ball bearing race in said casing, a ball within said race and a conical actuator mounted in said casing with the axis 105 of the contacting conical face of said actuator at an angle to the direction of movement of said ball, said ball bearing race being formed by two surfaces which form an angle with each other.

2. A caliper device comprising a spring pressed caliper plunger, a supporting casing for said plunger, a ball bearing race in said casing, a ball within said race, and a conical actuator mounted in 115 said casing with the axis of the contacting conical face of said actuator at an angle to the axis of said plunger, the spring of said spring pressed plunger tending to contact said plunger with said ball, said ball bearing race being formed by two surfaces which form an angle with each other.

The foregoing specification signed at Essen, Germany, this 22nd day of October, 1921.

KARL LAUER.
